VEHICLE TIMED AUTOMATIC TRAFFIC SIGNAL

Charles W. Neill, Syracuse, N. Y., assignor to
Crouse-Hinds Company, Syracuse, N. Y., a corporation of New York

Application June 13, 1930, Serial No. 461,010

7 Claims. (Cl. 177—337)

This invention relates to automatic traffic signals of the vehicle actuated type at isolated intersections. It has been common practice to employ a traffic signal operated by a timer which changes the signal indications on the respective streets in an arbitrary manner regardless of the actual number of vehicles using the intersecting streets. Improvements over this old style of arbitrary timer have recently been made, a notable example of which is the "normally go" traffic signal which indicates go to traffic on a main highway at all times except when a vehicle approaches on the intersecting cross street. Vehicle actuated means located in the traffic lane on the cross street operate the traffic signal to shift the go signal, which is normally displayed to the highway, to the cross street for a predetermined length of time sufficient to permit the vehicle approaching the intersection from the cross street to clear the intersection, after which the normal go signal on the highway is restored. While this type of signal is a great improvement over the old style arbitrary timer, it is open to certain objections. The go signal for the cross street is displayed for a predetermined length of time which must be sufficiently long to permit the slowest moving vehicle to clear the intersection during this go period. With fast moving traffic the go period on the cross street will persist for a much greater length of time than is actually needed by the cross street traffic. Thus traffic on the main highway is held up unnecessarily.

The principal object of this invention is to provide a traffic signal of the vehicle actuated type which will display a go signal to approaching traffic on a cross street for a period of time which is dependent on the speed of the traffic. Thus a long period will be provided for slow moving traffic and a short period for fast moving traffic. Unnecessary delay of highway traffic is thereby avoided.

A further object of the invention is to provide a traffic signal which has improved time extension means for extending the go period for a cross street in proportion to the number of vehicles approaching on the cross street.

A further object of the invention is to provide a traffic signal of the vehicle actuated type in which the go period for a cross street will be dependent on the speed of the cross street traffic, the traffic signal also having means for displaying a go signal indication to highway traffic for a predetermined minimum period of time.

A further object of the invention is to provide a traffic signal of the vehicle actuated type which

has improved means for remembering cross street traffic which actuates the vehicle actuated means just after the end of a cross street go period or during a minimum highway go period.

A further object of the invention is to provide improved switching means for changing the signal indications with the conventional amber period following the go signal indication without the use of cam timing means.

A further object and advantage is to provide vehicle actuated means which will be responsive to vehicles approaching from one direction but which will not start the traffic signal operating mechanism after a vehicle strikes a portion of the vehicle actuated means in sweeping a wide turn at the intersection.

Other objects and advantages of the invention will become apparent and will be pointed out as the description proceeds.

The invention consists in the novel features and in the combinations and constructions herein-after set forth and claimed.

In describing this invention reference is had to the accompanying drawings in which like characters designate corresponding parts in all the views.

Figure 1 is a perspective view of an intersection of a highway and cross street showing a traffic signal and the location, in the cross street, of the vehicle actuated means for controlling the traffic signal.

Figure 2 is a wiring diagram showing the relation of the various units of the traffic signal control mechanism.

Figure 3 is a wiring diagram showing the manner in which the signal lights are operated from the signal switching means.

Figure 4 is a chart showing the positions of the armatures for controlling the signal circuits during the various signal periods.

Location of vehicle actuated detectors

A traffic signal S is located in any convenient position so as to be visible to vehicles approaching on the intersecting streets. As shown in Figure 1 the signal S is of the type which is located in the center of the intersection. Two vehicle actuated means or detectors D', D² are located in the cross street on both sides of the intersection. These detectors are placed in the lane of the approaching traffic which will ordinarily be to the right of the center line of the street. The detectors D' and D² may be set in any spaced relation relative to one another. It is preferable, however, for the first detector D'

to be set back a sufficient distance from the intersection so that the signal will have time to change before the vehicle reaches the intersection thus permitting the vehicle to cross the 5 intersection without stopping or slowing down. Since it is conventional practice to display an amber signal to the highway before changing the signal indication to stop, the detector D' should be set back from the intersection sufficient distance to permit the highway amber period 10 to elapse before the vehicle on the cross street reaches the intersection. The detector D' operates the signal operating mechanism to change the signals so as to display a go signal to the 15 cross street and stop signal to the highway, this stop signal may be preceded by the conventional amber.

The detector D² starts the operating mechanism to restore the normal highway go signal 20 and cross street stop signal. It is desirable that the detector D² be so located in the cross street that any traffic on the cross street, which is waiting for a change in the signal, will stop over the detector D² or before reaching the detector D² but will not cross the detector D² before 25 stopping. Local conditions may determine the position and relation of the detectors D' and D² with respect to the intersection and to each other.

30 Any suitable vehicle actuated means may be used as the detector D' or D².

Vehicle actuated means such as a depressible treadle similar to that shown in the patent to Nelson No. 1,665,560 issued April 10, 1928, may 35 be used. However, in connection with the apparatus here disclosed, the contacts of the treadle are normally closed, and are opened by a vehicle passing over the treadle.

Effect of operation of the first detector

40 The vehicle actuated means are arranged so as to break the circuit to magnetic relays 10 and 11. When a vehicle actuates the detector D' the relay 10 will be de-energized and permit the armature 12 to drop. When the detector D' is 45 no longer under the influence of the vehicle the armature 12 will again be drawn up by the relay 10, into the position shown in Figure 2.

When a vehicle actuates the detector D² the 50 relay 11 will be de-energized and will permit the armature 13 to drop. When the detector D² is no longer under the influence of the vehicle, the armature 13 will again be drawn up into its raised position by the relay 11.

55 As a vehicle approaches the intersection on the cross street, it will actuate the detector D' to cause the relay 10 to permit the armature 12 to drop on the contacts 15 and 16. The contact 15 is hot at all times and when the armature 12 drops on these contacts 15 and 16, power will 60 flow through the armature 12 and the resistance 17, stick relay 18, and resistance 19, to the ground.

The stick relay 18 will be energized to throw its armature 20 into engagement with the contact 21. This establishes a new circuit from the contact 15 through the armature 12, contact 16, stick relay 22, armature 20, contact 21, stick relay 18, and resistance 19 to the ground. The stick relay 22 will attract its armature 25 into engagement with the contact 26. This establishes a new circuit from the armature 13, which is hot at all times, through the contact 30, armature 25, contact 26, stick relay 22, armature 20, 70 contact 21, stick relay 18, and resistance 19, to 75

the ground. This last described circuit will stick the relays 22 and 18, and the breaking of the circuit at contact 15 when the armature 12 rises after the vehicle on the cross street passes the detector D' will have no effect on the relays.

5

A conductor 35 connected to the circuit between the stick relay 18 and resistance 19, leads to a coil 36 of a motor 37. The motor may be of any conventional type suitable to operate the switching mechanism, and which is provided with 10 forward and reverse coils. The motor here shown is of the induction disk type provided with the coils 36, 39, to rotate the disk in opposite directions. When the operating mechanism is in normal position, as shown in Figure 2, the coil 36 15 is grounded through a stick relay 38 and brush 39, which contacts with a grounded conductor segment 40 of the commutator 41.

The purpose of the resistance 17 is to obtain a voltage drop across the stick relay 22 and the 20 purpose of the resistance 19 is to obtain a voltage drop across the motor coil 36.

When power is supplied to the motor coil 36 the motor 37 will operate in a forward direction, clockwise, as shown in Figure 2, and turn the 25 shaft 42 on which the commutator 41 is mounted.

As the commutator 41 turns in a forward or clockwise direction the grounded conductor segment 40 will move into contact with a brush 45 which connects with an armature 46 of the stick 30 relay 38. The brushes 39 and 45 are so spaced with relation to one another that the grounded conductor segment 40 will contact with the brush 45 before it breaks its contact with the brush 39. When the brush 45 makes contact with the 35 grounded conductor segment 40 a new circuit will be established from the stick relay 38 through a contact 48, armature 46, and brush 45 to the grounded conductor segment 40. This circuit will stick the relay 38 after the contact between the 40 brush 39 and grounded conductor segment 40 is broken.

Operation during forward rotation

The signal lights are operated by suitable 45 switching means, here shown as relay operated switches. The operation of the signals by these switches will be described later. The switches are operated by relays 50 and 51, which connect with suitable brushes on the commutator 41.

50

The relay 50 is connected by a conductor 52 with a contact 53. When the relay 38 is operated to attract the armature 46 contact is established between the contacts 53 and armature 46. The armature 46 is of the double type being 55 made up of two conductor sections insulated from one another. That part of the armature 46 which engages with the contact 48 connects with the brush 45. The part of the armature 46 which engages with the contact 53 connects with a 60 brush 45a.

As the commutator 41 turns in a forward or clockwise direction, the grounded conductor segment 40 will come into contact with the brush 45a. A new circuit is thus established through 65 the relay 50, one side of which is connected with a suitable source of current, conductor 52, contact 53, armature 46, and brush 45a to the grounded conductor segment 40. The flow of current through the relay 50 will cause the armature 70 55 to be drawn to the left in Figure 2, to change the signal indications so as to display the highway amber; the cross red remaining unchanged.

70

As the commutator 41 turns in a forward direction, a hot conductor segment 69 will come 75

in contact with a brush 51 which connects with the relay 51. The other side of the relay 51 is connected with a contact 62, but during the forward movement of the commutator 41, the armature 46 is out of engagement with the contact 62 and there is therefore no complete circuit through the relay 51.

As the commutator 41 continues to rotate in a forward direction the grounded conductor segment 40 will come into contact with a brush 65. This provides an additional ground connection for the relay 50, but is of no importance during the forward rotation of the commutator 41.

When the commutator 41 has rotated in a forward direction until the insulated segment 67 comes under the brush 45, the ground connection of the relay 38 will be broken and the armature 46 will be drawn back by a spring 68 out of engagement with the contacts 48 and 53 and into engagement with the contact 62. The circuit through the motor coil 36 is thus broken and the motor will stop. A shoulder 69 mounted on the commutator 41 contacts with a fixed abutment 69^a to prevent excessive coasting of the commutator 41 after the power to the motor has been shut off.

When the armature 46 is drawn back by the spring 68 into engagement with the contact 62, a circuit is established from the hot conductor segment 60 through the brush 61, relay 51, contact 62, armature 46, and brush 45^a, to the grounded conductor segment 40, the end of which is now located between the brushes 45 and 45^a.

When this circuit is established through the relay 51 the armature 70 will be moved to the left in Figure 2 to change the signal indications to display the highway red and cross street go signals.

The operating mechanism will now remain in this position until a vehicle actuates the detector D².

Effect of operation of the second detector

When a vehicle actuates the second detector D² the relay 11 will permit the armature 13 to drop out of engagement with the contact 39 and into engagement with a contact 72.

The breaking of the circuit between the armature 13 and the contact 39 will cut off the supply of power to the armature 25 and stick relay 22. This will cause the stick relay 22 to break, a spring 73 being provided to withdraw the armature 25 from the contact 26 when the relay 22 becomes deenergized.

The source of power to the stick relay 18, through the stick relay 22 is broken, but a new circuit is established from the armature 13 through the contact 72, and armature 20 to the contact 21 and stick relay 18. The break in the current while the armature 13 moves from the contact 39 to the contact 72 is of such short duration that the stick relay 18 will not break.

When a vehicle has passed the second detector D² the relay 11 will again attract the armature 13 and the contact between the armature 13 and contact 72 will be broken. This will break the circuit, just described, to the stick relay 18 and a spring 75 will draw the armature 20 to the left in Figure 2, out of engagement with the contact 21 and into engagement with contacts 76 and 77. The contact 76 is hot at all times and a new circuit is established from the contact 76 through the armature 20, contact 77, conductor 78, motor coil 80, conductor 81, contact 62, armature 46, and brush 45^a, to the grounded conduc-

tor segment 40. The flow of current through the motor coil 80 will cause the motor to rotate in a reverse direction so as to turn the commutator 41 in a counterclockwise or reverse direction.

Operation during reverse movement of the motor

As the commutator 41 rotates in a counterclockwise or reverse direction the grounded conductor segment 40 will move into contact with the brush 45, but during reverse movement the armature 46 will occupy the position shown in Figure 2 and no circuits are connected with that portion of the armature 46 which connects with the brush 45.

The commutator 41 will continue to rotate in a reverse direction and bring the insulated segment 85 under the brush 65. This will break the circuit through the relay 50, and the armature 55 will be drawn to the right in Figure 2, by a spring 86. This movement of the armature 55 will cause a change in the signals so that the cross amber signal is displayed, the highway red signal remaining unchanged. The position of the brush 65 is adjustable so as to determine how long the cross street go signal will persist after the commutator 41 begins its reverse rotation.

A brush 90, which is also adjustable, is set so that the hot conductor segment 60 will contact with this brush 90 at the same time that the insulated segment 85 comes under the brush 65. The brush 90 supplies power to the motor coil 80 in the event that the circuit from the contact 76 is broken after the cross street signal has changed from go to amber. This is to prevent time extension on the cross street of the amber or stop signals and will be fully explained in connection with the time extension feature of the invention.

As the commutator 41 returns to its original position, shown in Figure 2, the insulated segment 67 will come under the brush 61 and cut off the supply of power to the relay 51. The armature 70 will then be drawn to the right by a spring 88. This movement of the armature 70 will restore the signals to their original condition displaying the highway go and cross street red signals. The insulated segment 85 will come under the brush 45^a thus breaking the ground connection of the motor coil 80 and the motor 37 will stop, the commutator 41 coasting slightly until it reaches the position shown in Figure 2.

Minimum highway go period

The operating mechanism illustrated in Figure 2 provides a minimum highway go period. When the insulated segment 85 comes under the brush 65, during reverse rotation of the commutator 41, the relay 50 is deenergized and the armature 55 moves to the right to change the cross street signal to amber as previously described.

The commutator 41 continues its reverse rotation until the insulated segment 67 comes under the brush 61. The signals are then changed to their normal position of highway go and cross street red, but the time of this change may be adjusted by changing the position of the brush 61. The time required after the insulated segment 67 has come under the brush 61 for the commutator 41 to complete its reverse rotation and move through the first part of a following forward rotation, provides a minimum period for the go signal on the highway.

The time between the contact of the insulated segment with the brush 65 and the contact of the 75

Memory feature

insulated segment 67 with the brush 61 will be the cross street amber period and these brushes 65 and 61 should be so adjusted with respect to one another that a cross street amber period of proper duration is obtained.

The motor coil 80 may be so wound, or so placed with respect to the motor 37, that the reverse rotation of the motor 37 is at a slower rate than was the forward rotation. This is highly desirable in connection with the setting of the brushes of the operating mechanism so as to obtain the desired minimum highway go period. The maximum highway go period will depend entirely upon the density of the cross street traffic since the go signal is normally displayed to the highway at all times unless a vehicle crosses the vehicle actuated means in the cross street.

Time extension feature

20. The apparatus is designed so as to start a reverse rotation of the operating motor to restore the signals to their normal position within a very short time after a vehicle passes the second detector D². The length of time, after a vehicle passes the detector D², before the cross street go signal changes to amber is adjustable by changing the position of the brush 65 as above described. This time will depend on the width of the intersection and should be just sufficient so that when added to the cross street amber period a vehicle will be permitted to clear, or almost clear, the intersection before the display of the highway go signal.

In order to obtain efficient handling of the traffic, it is necessary that means be provided by which the go period for the cross street can be extended in order to permit a group of vehicles to cross during the same period. The time extension is provided by the operating mechanism shown in Figure 2.

If a vehicle crosses the detector D' at any time during the cross street go period and after the vehicle ahead of it has actuated the second detector to start reverse movement of the motor, 45 the stick relays 22 and 18 will be operated in exactly the same manner as previously described in connection with the first vehicle to cross the detector D'. No current will flow through the conductor 35, however, because the ground connections of the conductor 35 are broken; the brush 39 is in contact with the insulated segment 67, and the armature 46 is not in engagement with the contact 48. When the relay 18 is energized by this second vehicle passing across detector D', 50 the armature 20 is drawn to the right and the circuit from the contact 76 to the motor coil 80 is broken thus stopping the motor. The motor will remain stopped and the signals will remain in position displaying a go signal to the cross street 55 until the second vehicle has passed over the detector D². Reverse rotation of the motor will then be resumed, the mechanism operating as in the case of the first vehicle to cross the detector D².

If the second vehicle does not reach the detector 60 D', until after the cross street go signal has changed to amber, no time extension of the amber period will result. The stick relays 22 and 18 will be operated but they will not stop the reverse rotation of the motor. Power to continue the reverse rotation of the motor will be supplied from the hot conductor segment 60 which comes into contact with the brush 90 to supply power to the motor coil 80, when the cross street signal changes 65 to amber.

When a second vehicle on the cross street reaches the detector D' during the cross street amber period, or during the cross street stop period, but before the operating mechanism has completed its reverse rotation, means are provided by which the mechanism remembers such second vehicle.

This second vehicle will stick the relays 22 and 18 as previously described. When the commutator 41 has moved in a reverse direction until the ground conductor segment 40 contacts with the brush 39, a circuit will be completed from the stick relay 18 through the conductor 35, motor coil 36, relay 38, and brush 39 to the grounded conductor segment 40. The armature 46 will be drawn to the left, thus breaking the ground connection of the motor reverse coil 80. The motor will thus drive the operating mechanism forward 20 to give a cross street go signal to the waiting vehicles.

Signal switching means

The operation of the signal lights by the switching means is illustrated in Figure 3. The 25 relay 50, when energized, draws the armature 55 to the left to engage the contact point 95. When the relay 50 is not energized the armature 55 is held in engagement with a contact 96 by the spring 86.

The relay 51, when energized, draws the armature 70 into engagement with a contact 97. When the relay 51 is not energized the armature 70 is held in engagement with a contact 98 by the spring 88.

The armature 70 is connected with a suitable source of current so that it is always hot. The armature 55 is at all times connected to the ground.

When neither of the relays 50 or 51 is energized 40 and both armatures 55 and 70 are in their normal position, as shown in Figure 3, the signals will be in their normal position displaying highway go signal and cross street red signal. The circuit will be readily understood by reference to 45 Figure 3, and may be traced from the armature 70 through the contact 98, highway go signal, contact 96, and armature 55 to the ground. The cross street red signal is in a parallel circuit which may be traced from the armature 70 through the 50 contact 98, and cross street red signal to the ground.

When the relay 50 alone is energized, the armature 55 is drawn into engagement with the contact 95 thus breaking the circuit through the highway go signal and establishing a circuit from the armature 70 through the contact 98, highway amber signal, contact 95, and armature 55, to the ground.

When both the relays 50 and 51 are energized, 60 a circuit is established from the armature 70 through the contact 97, and highway red signal, to the ground. A parallel circuit is established from the armature 70, through the contact 97, cross street go signal, contact 95, and armature 55, to the ground.

When the relay 51 only is energized the circuit through the highway red signal remains, but the parallel circuit is now from the armature 70, through the contact 97, cross street amber signal, contact 96, and armature 55, to the ground.

While I have illustrated my invention in a preferred embodiment, various changes and modifications may be made therein without de- 75

parting from the spirit of the invention as set forth in the appended claims.

What I claim is:

1. A traffic signal for directing traffic at the intersection of two highways, including signals normally indicating go to one highway and stop to the other, and means for shifting and reshifting said signal indications to the respective highways, said shifting mechanism including first and second vehicle actuated means located in one of said highways in spaced apart relationship, and arranged to be successively actuated by traffic approaching the intersection on said highway, and switching means operable, upon actuation of the first detector, to shift the signal indications from stop to go on the highway on which the vehicle actuated means are located, and go to stop on the other highway, and operable, upon actuation of the second detector, to reshift said signals to their original indications, and cause said signals to display such indications for a predetermined minimum length of time before said signals can again be shifted by actuation of the first vehicle actuated means.

2. A traffic signal for directing traffic at the intersection of a highway and a cross street including a signal device having signals normally indicating go to the highway and stop to the cross street, and having a caution signal to indicate signal changes, means for shifting and reshifting said go-stop signals and operating said caution signal, including a first and second vehicle actuated means located in spaced apart relationship in the cross street, and arranged to be successively actuated by traffic approaching the intersection on said cross street, switching mechanism operable, upon actuation of the first vehicle actuated means, to shift said highway go signal to caution and after a predetermined time to shift the cross street stop signal to go, and the highway caution signal to stop, and operable, upon actuation of the second vehicle actuated means, to shift the cross street go signal to caution and subsequently the highway stop signal to go and the cross street caution to stop, and maintain the signals in said reshifted position a predetermined minimum period of time before they can again be shifted by actuation of the first vehicle actuated means.

3. A traffic signal for directing traffic at the intersection of a highway and a cross street including a signal device having signals normally indicating go to the highway and stop to the cross street, and having a caution signal to indicate signal changes, means for shifting and reshifting said go-stop signals, and operating said caution signal, including a first and second vehicle actuated means located in spaced apart relationship in the cross street, and arranged to be successively actuated by traffic approaching the intersection on said cross street, switching mechanism operable, upon actuation of the first vehicle actuated means to shift said highway go signal to caution, and subsequently shift said caution signal to stop on the highway and go on the cross street, and said switching mechanism being operable, upon actuation of the second vehicle actuated means, to reshift the cross street go signal to stop and the highway stop signal to go, and cause said highway go signal to persist a predetermined minimum length of time before said signals can again be shifted.

4. A highway traffic signaling device for intersecting highways including signals normally indicating go to one highway, and stop to the other, mechanism for shifting and reshifting said signals to reverse and to restore the indications to the

respective highways, said shifting mechanism including first and second vehicle actuated means located in one of said highways in spaced apart relationship, and arranged to be successively actuated by traffic approaching the intersection on said highway, and switching means operable, upon actuation of the first detector, to shift the signal indications from stop to go on the highway on which the vehicle actuated means are located, and go to stop on the other highway, and operable, upon actuation of the second detector, to reshift said signals to their original indications, and cause said signals to display such indications for a predetermined minimum length of time before said signals can again be shifted by actuation of the first vehicle actuated means.

5. In a highway traffic signaling device for intersecting highways including signals normally indicating go to one highway, and stop to the other, means for shifting and reshifting said signals to reverse and restore the signal indications to the respective highways, said shifting means including a first and a second detector located in one of said highways in spaced apart relationship, and arranged to be successively actuated by traffic approaching the intersection on said highway, and switching means operable, upon actuation of the first vehicle actuated means, to shift said signal indications from go to stop on one highway, and stop to go on the other highway, and operable, upon actuation of the second vehicle actuated means, to reshift said signal indications to their initial display, and operable, upon a subsequent actuation of the first vehicle actuated means during the reshifting of the signals, to stop said reshifting, and upon subsequent actuation of the second vehicle actuated means to complete said reshifting of the signal indications, and to cause said signals to display the initial indications for a predetermined minimum length of time before they can again be shifted by actuation of the first vehicle actuated means.

6. A traffic signal for directing traffic at the intersection of a highway and a cross street including signals normally indicating go to the highway and stop to the cross street, and also including a caution signal to indicate signal changes, means for shifting and re-shifting said go-stop signals, and operating said caution signal, including first and second vehicle actuated means located in spaced apart relationship in the cross street, and arranged to be successively actuated by traffic approaching the intersection on said cross street, said shifting and re-shifting means also including switching mechanism operable, upon actuation of the first vehicle actuated means, to shift said highway go signal to caution, and subsequently shift said caution signal to stop, and shift the stop signal on the cross street to go, and said switching mechanism being further operable upon actuation of the second vehicle actuated means to reshift the cross street go signal to caution, and subsequently shift said caution signal to stop on the cross street, and said stop signal to go on the highway, and cause said signals to display go to the highway and stop to the cross street for a predetermined minimum time before said signals can again be shifted, and said shifting mechanism being further operable upon actuation of the first vehicle actuated means during the display of the go signal on the cross street to arrest said reshifting until subsequent actuation of the second vehicle actuated means.

7. A traffic signal for directing traffic at the intersection of a highway and a cross street in-

cluding signals normally indicating go to the highway and stop to the cross street, and also including a caution signal to indicate signal changes, means for shifting and re-shifting said go-stop signals, and operating said caution signal, including first and second vehicle actuated means located in spaced apart relationship in the cross street, and arranged to be successively actuated by traffic approaching the intersection on said cross street, said shifting and re-shifting means also including switching mechanism operable, upon actuation of the first vehicle actuated means, to shift said highway go signal to caution, and subsequently shift said caution signal to stop, and shift the stop signal on the cross street to go, and said switching mechanism being further op-

erable upon actuation of the second vehicle actuated means to reshift the cross street go signal to caution, and subsequently shift said caution signal to stop on the cross street, and said stop signal to go on the highway, and cause said signals to display go to the highway and stop to the cross street for a predetermined minimum time before said signals can again be shifted, and said shifting mechanism being further operable upon actuation of the first vehicle actuated means during the display of the cross street caution signal, or the highway go signal, to cause said signals to again be shifted from their normal indication to stop on the highway and go on the cross street.

15

CHARLES W. NEILL.
